GAS LIFT

John M. Courtney, Vivian, La.

Application May 27, 1941, Serial No. 395,327

4 Claims. (Cl. 103—232)

This invention relates to an apparatus for flowing or pumping a well in which there is not sufficient formation pressure for the well to flow by itself. It is particularly applicable to deep wells such as oil-wells but the principles can be applied to shallow wells or to wells from which fluids other than oil are to be withdrawn. It can also be applied to aid the natural flow from wells which have sufficient formation pressure to flow by themselves but in which it is desirable to increase the rate of flow.

The common practice in oil wells is to permit them to flow under their own natural pressure as long as they will do so and then to apply a mechanical reciprocating pump to complete the removal of the oil. While this is the method that is at present in general use it is a cumbersome unsatisfactory method. Because suction will only raise oil for a distance of some 35 feet it is necessary to have the pump near the bottom of the well so that it can exert pressure instead of suction on the column of oil coming out of the well. This involves the use of pump rods of lengths of 5000 feet or greater in many instances and when the pump plunger or the valves become worn it is necessary to remove the pump from that depth to replace the worn parts. Furthermore, the collars on the pump rod wear rapidly and all the pump parts do likewise because of the small particles of grit that remain in the oil and the whole device is mechanically inefficient because of the relatively long pump rods that must be reciprocated to perform the pumping operation.

As an alternative to the use of reciprocating mechanical pumps, gas lifts of various kinds have been proposed. None, up to the present time, however, have been very successful because none were so arranged as to avoid erosion and plugging, nor were they in most instances efficient enough to lift a sufficient amount of oil with a sufficiently small expenditure of energy in operation.

The present invention is directed to a gas lift type of pumping apparatus but differs from previous devices of this type in that it is arranged so that the gas pressure is never on the formation from which oil is being pumped, so that the possibility of clogging or plugging is substantially eliminated, so that the operation of the device can be readily started without the necessity of extended swabbing of the pump tubing, so that the operation thereafter can be carried on efficiently with a minimum of gas, as compared to the amount of oil lifted, so that the apparatus

will not be injured by the operation of a swab in the pump tubing, and so that the gas used in the pumping operation may be readily recovered and re-used.

Briefly, the apparatus of the present invention consists of a string of pump tubing which extends down to the formation to be pumped, a packer near the bottom of the string of tubing to seal the tubing to the well casing or wall, preferably a filter or a perforated element below the packer to filter the oil that enters the pump tubing, a particular type of gas lift mechanism in the pump tubing above the packer and the necessary equipment on the surface for forcing gas down into the well around the pump tubing, taking gas and oil from inside of the pump tubing at the surface, separating this gas and oil, and recompressing the gas for further use.

The gas lift mechanism forms the lower end of the tubing string and includes a standing valve which permits oil flow upward in the tubing but effectively prevents any flow of either oil or gas downward into the formation. Above this is a device which receives gas under pressure from outside of the pump tubing and directs this gas upwardly within the pump tubing so as to suck fluid from beneath it and blow any fluid above it upward and out of the well. This mechanism is of particular interest because of its detailed construction which provides a filtering element for the gas before it enters the tubing string, a series of metering orifices or choke buttons which limit the amount of gas that can pass into the tubing at any particular pressure and a series of pressure valves that prevent gas from entering the pump tubing below a predetermined pressure and also prevent oil from within the pump tubing from passing out through the gas lift mechanism into the casing outside of the pump tubing.

Incidentally, there are several inlets for gas into the pump tubing one or more of which are considerably larger than the others and are set for release only at a relatively high pressure so that if a relatively high pressure is placed on the gas going into the well these openings begin to function and allow a strong blast of gas to pass up the well thus clearing the well for subsequent operation and a lower pressure. The metering valves are so constructed that they do not readily become plugged with sediment and the pressure valves are so arranged that they protect the metering valves from sediment in the oil and at the same time are not readily clogged or eroded themselves.

Above the gas lift is positioned, within the pump tubing, a bushing or construction that prevents a swab lowered into the tubing from striking the pressure valves and injuring them. At the top of the well there is a valve arrangement which permits gas to be passed down into the well outside of the pump tubing and permits the contents of the pump tubing to be discharged into a settling tank. The settling tank is constructed so that gas from the top of the tank passes off to a compressor, from the compressor through a condenser and then into a storage tank. Liquid from the bottom of the settling tank passes to storage and a float valve arrangement controls the level of the liquid in the settling tank so that it never gets low enough for gas to escape to the liquid storage. From the gas storage tank, gas is passed through a heater to a reducing valve and then into the well outside of the pump tubing. The heater at the reducing valve prevents the gas from freezing when its pressure is reduced.

Additional details and advantages of this invention will be apparent from the following detailed description of the preferred embodiment thereof but it is to be understood that the principles of this invention are not limited to that particular embodiment except as specified in the claims.

In the drawings:

Figure 1 is a schematic view partly in section of a preferred form of the apparatus of this invention;

Figure 2 is a sectional elevation view of the gas lift;

Figure 3 is a top view of the gas lift;

Figure 4 is a top sectional view of the gas lift taken on line 4-4 of Figure 2; and

Figure 5 is a detail view showing one of the valve cages.

As illustrated in Figure 1, the apparatus is arranged for pumping an oil well 10 which includes a casing 11 which extends down to the top of a formation 12 from which oil is to be removed. Extending out of the lower end of the casing 11 into the formation 12 is a perforated cup-shaped member 13 supported at the bottom of a string of pump tubing 14. Oil from the formation and of course water, gas or any other fluids that are in the formation, enter through the perforated member 13 and pass upward through the pump tubing.

Just above the perforated member 13 is a packer 15 which is shown only diagrammatically since packers are old in the art. This packer serves to seal the outside of the pump tubing to the inside of the casing so that there will be no communication from the space between the pump tubing and the casing to the formation being pumped.

At some place in the pump tubing preferably below the gas lift, is a standing valve 16 which is no more than a check valve to prevent downward flow of fluid in the pump tubing. Above this in the pump tubing string is the gas lift 17 itself. This part of the device is shown in greater detail in Figures 2, 3, 4 and 5. This device has a central opening 18 which connects the interior of the pump tubing above and below the gas lift and, as shown in the drawings, four gas inlets which cause the pumping effect. Of these, three 19, 20 and 21 are shown as relatively small and arranged to open at a relatively low pressure, whereas the fourth, 22, is relatively large and opens only at a much higher pressure. For ex-

ample, the three smaller openings may open at a pressure of around fifteen pounds per square inch and the one larger opening may open at around seven hundred pounds per square inch. The larger opening has preferably at least from ten to twenty times the capacity of the smaller openings, however, so that when it does open a large volume of gas flows through it.

The openings 19, 20, 21 and 22 are formed by vertical openings 23, extending from the top of the main body element 24 of the gas lift, well down into its mid section where they intersect openings 25 extending radially inward from the outer periphery of the body member. In order to accurately govern the flow of gas through these openings, a metering orifice member or choke button 26 is screwed into each of these openings. A recess 27 is provided in the body member 24 for each of these metering orifice members so that the head does not extend outward beyond the periphery of the body member.

Each of these metering members 26 has a longitudinal opening 28 and a transverse intersecting opening 29 through which gas may enter the vertical opening 23 in the body member. Since these openings may be accurately drilled to size they provide a means for accurately controlling the amount of gas which enters the opening at any particular pressure. It may be noted in Figure 2 that the opening in the metering member which supplies the large opening 22 is considerably larger than the opening in the member opposite it which supplies one of the smaller openings 19. By providing the intersecting transverse opening 29 the possibility of plugging of the metering members is greatly reduced.

Around the body member 24 of the gas lift is a perforated metal screen 30 which covers the metering members and prevents, to a large extent, the entrance of foreign materials that might plug the metering orifices.

At the outlet ends of the various gas openings 19, 20, 21 and 22 are spring pressed ball valves each covered by a cage 31. Each of the balls 32 rests in a seat formed in the body member 24 and is pressed downwardly by a spring, 33 and 34 which is held in place by a valve cage 31. The valve cages 31 are so constructed that although they hold the springs in place, gas which passes upward past the balls 32 is not hindered to any great extent in its upward and outward flow and is able to sweep on up the pump tubing and carry with it any oil, water, gas or other fluid that comes up through the opening 18 in the body member. It will be noted from Figure 2 that the valve spring 34 on the valve for the larger opening 22 is larger than the spring on the valve for the smaller opening 19 and it should be mentioned that this spring is stronger so that it holds the valve closed except under a much higher pressure.

Above the gas lift is a constriction 36 in the pump tubing which constriction prevents a swab, if used, from passing down and striking the valves in the gas lift.

At the surface of the ground is the usual "Christmas tree valve" 37 with a gauge 38 which indicates the pressure of the gas between the pump tubing and the casing and a gauge 39 which indicates the pressure of the fluid in the pump tubing. Gas is supplied to the space between the pump tubing and the casing from a gas storage tank 39 through a heater 40 which prevents the gas from freezing when the pres-

sure on it is reduced, and then through a reducing valve 41. A gauge 42 is provided just beyond the reducing valve to determine the pressure of the gas at that point and a control valve 43 is provided between the reducing valve and the well to control the entrance of the gas into the well.

As the fluid comes out of the pump tubing it passes through a valve 44, a pipe 45, a second valve 46, a pipe 47 and into a separator 48. In this separator the liquid is allowed to settle to the bottom and the gas is withdrawn through a pipe 49, recompressed in a compressor 50, cooled in a condenser 51 and returned to the gas storage tank 39.

The liquid from the separator 48 is drawn off through a pipe 52 under the control of valve 53 and sent to storage tanks for further use. The valve 53 is controlled by a float in the separator 48. This avoids the possibility of the liquid level in the separator becoming so low that gas passes to the liquid receptacle.

A careful inspection of the arrangement of parts in the device described and particularly in the gas lift itself will reveal the fact that there is no place where sediment from the oil or other fluid being pumped can readily settle into the valves or metering orifices and thus cause misfunctioning or a failure to function of the device.

In some instances in starting the operation of the device it will be desirable to clean out the pump tubing but this is seldom necessary. Ordinarily, it will only be necessary to raise the pressure between the casing and the pump tubing to such a point that the high pressure valve opens and this will immediately blow the pump tubing free of excess oil and start the operation of the device. Thereafter the pressure can be reduced to a point where the high pressure valve closes, the discharge of gas into the pump tubing is entirely through the low pressure valves, the standing valve will open and allow fluid to pass upward through the well and the operation will thereafter continue as long as a relatively low gas pressure is applied and there is fluid in the well to be pumped.

I claim:

1. In a gas lift pumping device for use in a well and comprising a tube adapted to be lowered into fluid in a well, means to seal the outside of said tube to the inside of the well at a point near its lower end, means to force gas under pressure into the space between the outside of the tube and the inside of the well above the sealing means, and means to inject into the tube in such a manner as to create an upward flow therein, the gas from outside of said tube, the improvement that comprises in the means to inject the gas into the tube, a plurality of metering orifices for controlling the rate of flow of

gas into the tube and a pressure sensitive check valve positioned between each metering orifice and the interior of the tube to prevent outward flow from the interior of the tube, at least one of said metering orifices being larger than at least one other of said metering orifices and the check valve for the larger orifice being biased so as to remain closed except at a relatively high differential pressure.

2. In a gas lift pumping device for use in a well and comprising a tube adapted to be lowered into fluid in a well, means to seal the outside of said tube to the inside of the well at a point near its lower end, means to force gas under pressure into the space between the outside of the tube and the inside of the well above the sealing means, and means to inject into the tube in such a manner as to create an upward flow therein, the gas from outside of said tube, the improvement that comprises as the means to inject the gas into the tube, a cylindrical body member having a central longitudinal opening therethrough, through which fluid may pass upward, a plurality of longitudinal openings arranged around the first mentioned opening and extending from the top downward only partly through said body member, an opening from each of the second mentioned longitudinal openings extending radially to the outside of said body member, a supplemental member having a metering orifice therein positioned in each of said radial openings, a pressure sensitive check valve at the upper end of each of the second mentioned longitudinal openings, means connecting a tubing to the lower end of said cylindrical member so that it will be in communication with the central opening at the bottom of the cylindrical member and means connecting the top of the cylindrical member with a section of tubing so that the interior of that section of tubing will be in communication with the upper end of all of the longitudinal openings.

3. In a gas lift pumping device as defined in claim 2 the additional improvement that comprises having the check valves so arranged that each check valve comprises a ball, a spring pressing said ball downwardly against a seat formed in the top of one of the second mentioned longitudinal openings and a cage for holding the ball and the spring which cage is so constructed as to direct the flow of gas outward and upward from the second mentioned longitudinal opening.

4. In a gas lift pumping device as defined in claim 2 the additional improvement that comprises a check valve in the tubing below the body member to prevent the downward flow of fluid therein.

JOHN M. COURTNEY.
